HEATED SHAVE CREAM DISPENSER

William J. Cook, Trumbull, Conn., assignor to
General Electric Company

Filed Jan. 31, 1972, Ser. No. 222,450

Term of patent 7 years

Int. Cl. D6—06

U.S. Cl. D6—95

FIG. 1.

FIG. 2.

FIG. 3

FIG. 4.

FIG. 5.

FIG. 6.

FIG. 1 is a perspective view of a heated shave cream dispenser embodying my new design;

FIG. 2 is a top plan view thereof;

FIG. 3 is a front elevational view thereof;

FIG. 4 is a bottom plan view thereof;

FIG. 5 is a rear elevational view thereof; and

FIG. 6 is a right side elevational view thereof.

I claim:

The ornamental design for a heated shave cream dispenser, substantially as shown.
